UNITED STATES PATENT OFFICE.

FRANK H. BARBER, OF HOLYOKE, MASS., ASSIGNOR OF ONE HALF TO THE
GEORGE R. DICKINSON PAPER COMPANY, OF SAME PLACE.

SPOOL-WINDER.

SPECIFICATION forming part of Letters Patent No. 327,511, dated October 6, 1885.

Application filed April 3, 1885. Serial No. 161,113. (No model.)

To all whom it may concern:

Be it known that I, FRANK H. BARBER, a citizen of the United States, residing at Holyoke, in the county of Hampden and Commonwealth of Massachusetts, have invented a new and useful Combination Spool-Winder, of which the following is a specification, reference being had to the accompanying drawings, forming a part thereof.

10 My invention relates to improvements in spool-winders carrying two spools or cylindrical rolls, upon which paper or other material in long sheets is wound; and the objects of my improvements are to provide a self-contained device upon the spool-shaft which shall automatically equalize the tension and wind the material with equal tightness upon the two spools. I attain these objects by means of the mechanism illustrated in the accompanying drawings, in which—

Figure 1 is an external view of my invention complete, and Figs. 2, 3, 4, and 5 are detailed views on a larger scale of the various parts thereof.

25 Similar letters refer to like parts throughout the several views.

In Fig. 1, A is the spool-shaft, which is supported in suitable bearings and revolved by power in the usual manner.

30 B and B' are the two spools, which are loose upon the shaft A, and are driven by the mechanism between them. This driving mechanism consists, first, of a collar, C, secured to the shaft A by set-screws, and having arms upon two opposite sides, upon which the bevel-pinions D D freely revolve; and, secondly, of bevel-gears E E', which are loose upon the shaft A and connected with the spools B B'. The spools are held in place by a flange, F, fitting the end of the spool and loose upon the shaft, and a collar, G, set-screwed to the shaft, which arrangement prevents lateral motion of the spool, but allows it to revolve independently of the shaft. The spool B' is provided 40 with a similar flange and collar. (Not shown in the drawings.)

The result of this construction is that when the shaft A is revolved the collar C turns with it, and the pinions D D revolve or have an orbit around the axis of said shaft. If both spools are free to move, the gears E and E' bear

equally upon the pinions D D, said pinions remain stationary upon their axes, the two gears are revolved at the same velocity as the collar C, and carry with them the spools B and B'. 55 If the spools are winding material upon them and the tension or resistance is the same on each, the result is the same, for the resistance upon the spool B which is communicated to the gear E, and tends to revolve the pinions 60 in one direction upon their axes, is exactly balanced by the pressure of the gear E' in the opposite direction, and hence the pinions remain stationary on their axes, but move in space about the shaft A and drive the two 65 spools at equal velocities; but suppose the resistance on spool B exceeds that on B', the pressure of the gears upon the pinions is unbalanced, the pinions rotate and allow the spool B to turn slower than the shaft A, and 70 (as all the gearing is in mesh) cause the spool B' to turn faster than the shaft A until the balance readjusts itself, which it will in this manner do automatically, and wind the material with equal tightness upon the two spools. 75

The construction of the parts in detail is shown more clearly in Figs. 2 to 5, inclusive. In Fig. 2 is shown the spool-shaft A, the flange F for the end of the spool, and the collar G, which is secured to the shaft by the set-screw 80 g, and prevents lateral motion of the spool without interfering with freedom of revolution. Fig. 3 is a front view of the flange F, showing the projections f f, which fit corresponding slots in the spools, (indicated at b b 85 in Fig. 4.) In Fig. 5 are shown the details of the driving mechanism. C is the pinion-collar, secured to shaft A by set-screws e. The pinions D D have a running fit on the arms K K, and are held in place by bolts s s and washers t. The collar C is continued along the shaft on each side by the projecting cylindrical portions L, with grooves l. The gears E E' have cylindrical projections M M', of proper form to receive said parts L L, and screws m m, &c., 95 to enter the grooves l. This construction keeps the gears in place while the spools are being changed. When the spools are in place, they resist the thrust on the gears, so that there is no strain on the screws m m. 100

On the outer side of the gear E is a cylindrical part, N, over which fits the sleeve O.

This sleeve has a flange at one end similar in form to the flange F, already described, which fits the end of the spool B. The sleeve O is slotted at o, and has ears V at each side of the slot, and bolts W for the same, by means of which the sleeve O may be securely clamped to the gear E. The connection is further insured by means of the feather or spline x. The object of this construction is to allow adjustment of the sleeve upon the gear to accommodate different lengths of spools. The gear E' and sleeve O' are connected in a similar manner.

Having fully described my invention, what I desire to claim, and secure by Letters Patent, is—

1. The combination, with the shaft A and the spools B and B', of the collar C, secured to said shaft, and having two arms, K, two pinions, D, adapted to rotate on said arms, the gears E and E', meshing with said pinions, and the sleeves O and O', connected with said gears and spools, substantially as set forth.

2. The combination, with the shaft A, of the collar C, secured thereto, and having arms K, and cylindrical portions L, provided with grooves l, the pinions D, adapted to rotate on said arms, the gears E and E', having cylindrical projections M M', fitting over the said portions L, and provided with screws m, engaging said grooves, substantially as set forth.

3. The combination, with the shaft A, of the collar C, secured thereto, and having arms K, the pinions D, adapted to rotate on said arms, the gears E and E', meshing with said pinions, and having cylindrical parts N, and the slotted sleeves O and O', splined to said parts N, and having clamping-ears and bolts, whereby the adjustment of the sleeves relative to the gears, to accommodate different lengths of spools, may be effected, as set forth.

FRANK H. BARBER.
